MANUFACTURE OF HYPODERMIC NEEDLES

Samuel James Everett, Thornton Heath, England, assignor to S. & R. J. Everett & Company Limited, Thornton Heath, England, a British company

Application May 1, 1953, Serial No. 352,439

Claims priority, application Great Britain May 6, 1952

7 Claims. (Cl. 29—528)

This invention relates to the mounting of hypodermic needles in the mounts which enable them to be attached to the outlet of a hypodermic syringe, and is particularly concerned with the manufacture of needles and mounts in which a comparatively soft metal bush surrounds the needle where it emerges from the mount and extends a short distance towards the point of the needle, as described in the specification of British Patent No. 651,605 granted to Samuel James Everett.

These needles are usually packed in clips on a metal or plastic card which can be packed in a box or container, preferably of metal; a convenient number for each box is twelve needles mounted on a single card in six clips at either end. These needles have previously been manufactured singly, the soft metal bushes being die-cast, a number at a time, on a single runner, separated into individual parts, a needle inserted into each bush, and the whole inserted in the mount and swaged into position individually. In such needles in which the point is formed by grinding the needle away at an angle, a flat formed on the mount should face radially in the same direction as the face formed by grinding the needle.

The present invention enables a much higher rate of production to be achieved by manufacturing the needles and mounts in batches which conveniently correspond to the number held in clips at one end of the packing card, which in the example quoted above, would be six. The handling of the parts during manufacturing is reduced, as well as the risk of damaging the needle points.

According to the invention, the complete needles are manufactured in sets or batches and, to keep the needles together in their sets and located relative to each other, so that the complete set is easily handled and the needles are correctly spaced for fitting into the various tools, the soft metal bushes are cast around the needles of a set on a continuous runner from which they are not separated until the needles and mounts are complete.

The number of needles in a set may conveniently be the number required at a time for packing. Thus when the needles are packed in dozens, six in clips on each side of the box, it is convenient to make the needles in sets of six, and the various stages in the manufacture of a set of six needles is illustrated, by way of example only, in the accompanying drawings in which:

Figure 1 shows six needles set in a mould in which the metal bushes have been cast on a common runner;

Figure 2 shows the six needles with the bushes round them on a common runner;

Figure 3 shows the runner and needles mounted in a die-nest;

Figure 4 shows the first stamping process;

Figure 5 shows the second stamping process;

Figure 6 shows the fitting of the mounts;

Figure 7 shows diagrammatically a six-hammer press;

Figure 8 shows an enlarged detail of Figure 7;

Figure 9 shows a set of spring clips for holding the finished needles;

Figure 10 shows the needles mounted for inspection;

Figure 11 shows a loading jig open;

Figure 12 shows a loading jig closed; and

2

Figure 12 shows the arrangement of clips in the bottom of the packing box.

In Figure 1 the six needles 1, are mounted side by side with their points 2, all facing the same way as shown, in a mould consisting of a lower part 3, and an upper part 4, having six mould cavities 5, for the soft metal bushes and a longitudinal cavity 6, connecting the cavities 5 for the runner. Molten low melting point metal may be introduced through the hole 7. The result is a runner 8, from which the six bushes 9 project, surrounding the shafts of the needles 1 which pass right through the bushes and project slightly from the upper surface as seen in Figure 2. This is now set in the die-nest shown in Figure 3, consisting of a die-body 10, having six suitably spaced cavities 11, in which are die-inserts 12, the tops of which projects above die-body 10. These inserts have a central hole to take the shafts of the needles and are coned at the top as shown at 13, so as to form a sharp edge round the ring of a diameter rather greater than the diameter of the metal bushes 9. This die-nest with the runner and needles in place, is now passed to a first punch which comes down on the needles 1 as shown in Figure 4. The punch has a cavity 14, which passes over the bushes 9, and the tip of the punch bears on the runner 8 causing the coned head of the insert 13 to penetrate a short distance into the runner. The primary purpose of this punch, however, is to force the upper end of the needle shaft down flush with the top of the bush 9.

The next punch shown in Figure 5 comprises a central punch 15, the head of which is coned so as to drive the shaft of the needle yet further down through the bush 9. This punch is surrounded by a sleeve 16, which is urged by a spring downwards over the head of the punch 15. Except for an axial bore fitting round the head of the punch 15, the lower end of the sleeve 16 is closed. The axial bore is coned at this lower end so as to fit over the bush 9. The sleeve 16 is free to slide on the punch 15 but its movement is limited by the pin 17, carried by the punch 15 and projecting through a slot 18, in the sleeve. When this punch is bearing down onto the head of the bush 9, the coned part of the sleeve 16 fits over the bush 9 and squeezes it slightly into the needle and serves to locate the axial bore accurately relative to the bush 9. When the sleeve 16 can descend no further the punch 15 continues to descend and engages the head of the needle shaft 1 and forces it part of the way through the bush 9 as shown, at the same time forming a coned recess in the top of the bush. The pressure exerted in this operation causes the sharp rim of the insert 12 to penetrate still further through the runner 8.

After this operation the die-nest with the needles and runner is removed from the press, and turned brass or stamped metal mounts 19, are fitted over the bushes 9. The assembly then passes to the 6-hammer press shown in Figures 7 and 8. In Figure 7 the mechanism of the press is shown diagrammatically and comprises a vertical bar 20, arranged to slide vertically in guides and carrying a punch 21 at its lower end. The punch 21 is locked into the lower end of the bar 20 by a set screw 22. Above each bar a hammer 23 is mounted, pivoted to turn about an axis 24, and actuated by a push rod 25, having a follower roller at its lower end 26, which rides on the surface of a triple throw cam 27 on shaft 28. To raise the punches clear of the work a rocker arm 29 is provided pivoted at 30 and having one end engaging in a notch 31 of the vertical bar 20. The other end of the rocker arm 29 is engaged by the upper end of the control rod 32, which is connected at its lower end by a link 33 to a pedal 34 pivoted at 35. Thus when the pedal is depressed as shown in Figure 7 the punch 21 is lowered and the follower 26 engages the surface of the cam 27. When the pedal 34 is released a spring 36 causes it to turn to raise the punch

21 and the hammer 23 is lifted by the vertical bar 20 so that the follower 26 is carried clear of the cam 27. The action of the punch 21 is shown in Figure 8. It has a cylindrical part 37, which enters the bore of the metal mount and the coned tip of the part 37 engages the bush 9 swaging it into tight and intimate contact with the mount 19, and the shaft of the needle 1. Three blows of the hammers 23 are sufficient, that is to say one revolution of the shaft 28, and this also causes the head of the die-
5 insert 12 finally to penetrate through the runner 8 as shown in Figure 8. The punch 21 is now raised again and the holder 38, having six spring clips 39 spaced at the same intervals as the mounts 19, is fitted on the mounts 19 which are then removed from the die-nest. The runner 8 is left behind and can be returned for remelting.

The points of the needles are now passed over a buffing wheel to remove any burrs and the needles are now tested, after which they are passed for inspection still set in the holder 38, and mounted on the inspection jig shown in Figure 10 comprising six spigots 40 mounted on a bar 41. The spacing of the spigots is the same as the spacing of the clips 39, so that the needles may be mounted directly on these spigots and the holder 38 removed. The spigots are arranged so that when the needles are mounted on them they are immediately beneath a powerful magnifying glass through which they are inspected. The needles can be freely rotated on the spigots 40 for this purpose. After inspection the holder 38 is refitted and the needles removed and they are then transferred to the apparatus shown in Figures 11 and 12 for arranging suitably for packing in flat tin boxes. Figure 13 shows the arrangement of spring clips 43 projecting upwards from a card of plastic material 42, through holes in which the spring clips project. Six needles are mounted at each side of the card 42 with their points projecting inwards, and, in the example shown, for economy of space alternate needles at each side are staggered as shown, so that the mounts do not foul each other. The spacing of the clips 43 in each set of six clips is thus staggered and closer together than the spacing of the spring clips 39 on the holder 38. The apparatus shown in Figures 11 and 12 is designed to receive needles from the holder 38 and adjust their spacing automatically to correspond with the arrangement of the spring clips 43.

The apparatus consists of 6 metal bars 44 mounted between guides 45 and each provided at one end with a spigot 46 to fit a needle mount. The right hand bar as seen in Figure 11 is secured to the guides 45 and the bars are linked together by pivoted toggle links 47 as shown. The left hand bar is provided with a hand knob 48 and its movement towards the left in Figure 11 is limited by a stop bar 49. In the position of Figure 11 all the spigots 46 are in line and spaced to correspond to the spacing of the clips 39 of the holder 38, so that the needles held in the holder 38 can be fitted directly onto the spigots 46. When this has been done the holder 38 is removed and the knob 48 pushed towards the right closing up the spacing of the bars 44, which are of such width that when they are together the mounts are spaced a distance apart equal to the separation of the spring clips 43, while the toggle linkages 47 cause alternate mounts to be staggered as shown, so that the mounts are all ready to have the spring clips 43 applied to them. All six needles are thus mounted on the card 42 at once and are then removed from the loading jig. A further six needles are fitted to the clips on the opposite side of the card 42, which is then packed in its box.

This method of adjusting the spacing of the needles by simultaneously moving the members carrying the spigots 46 can be achieved in various other ways; for instance, by cams or other types of linkage such as a lazy tong. The mechanism chosen will depend of course, on the arrangement of the needles when they are packed, and may be used to increase the distance between the needles as well as to decrease it. This may be necessary in packing needles in sterile foil or plastics packs, when the

needles, in sets of, say, six, are spaced side by side without staggering and packed each in an envelope of foil or thermoplastic material the envelopes being made in strips and later severed from each other. For example, the spacing of the needles during manufacture as described may be one half inch, which may have to be increased to one and a quarter inches for packing in this way.

The method of manufacture according to the invention is applicable to any type of needle in which the needle shaft is held in the mount by a cast bush. Thus double ended needles for use for injection from ampoules may be made in this way, either with turned or stamped mounts of the type shown, or with a central ball for mounting, or with a central transverse plate or cam for engaging the 15 syringe outlet.

I claim:

1. A process of securing hypodermic needles into mounts by which they may be attached to a hypodermic syringe, by means of soft metal bushes surrounding the shafts of each needle, the bushes being swaged into bores in said mounts comprising casting a plurality of said bushes around a like number of said needles simultaneously on one continuous runner at points intermediate the ends of said needles, sliding said needles axially in said bushes to position said bushes at the rear ends of said needles, fitting a mount over each of said bushes, swaging said bushes into intimate contact with said needles and said mounts, and separating said bushes from said runner.

2. A process according to claim 1, in which the bushes are separated from the runner during the swaging operation.

3. A process according to claim 2, in which each bush is separated from the runner by the sharp edge of one 35 of a set of circular dies through which the shafts of the needles are passed, and on which the runner rests during the fitting of the mounts and swaging of the bushes.

4. A process according to claim 1, in which, after the bushes have been cast, the shafts of the needles are pressed 40 through the bushes so as to be flush with the ends of the bushes, after which the needles are pressed through the bushes still further and the mouth of the bores of the bushes opposite to the points of the needle shafts are axially coned.

5. A process according to claim 4, in which the runner 45 rests on the dies during the pressing operation and is partially cut through by the dies during this operation.

6. A process according to claim 2, in which after the bushes have been separated from the runner, needles are grasped and held in a like number of similarly positioned 50 spring clips from which they are transferred to a like number of parallel spigots, after which the positions of the spigots are simultaneously adjusted to move the needles into the correct position for packing, the number of needles in a set corresponding to the number required for packing at one time.

7. A process according to claim 6, in which the needles are eventually packed side by side in rows, alternate needles being staggered, and the spigots on which they are mounted prior to packing are arranged on parallel 60 members linked by toggle linkages so that when the linkages are extended, the spigots are side-by-side in line with a spacing equal to the spacing of the bushes on the runner, and when the members are close together the toggle linkages move the spigots, and therefore the mounts, into a position in which the needles are spaced and staggered ready for packing.
